(57) **CLAIM**

We claim the ornamental design for a pod light, as shown and described.

DESCRIPTION

FIG. 1 is a perspective view of the pod light showing the new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

UNITED STATES PATENT AND TRADEMARK OFFICE
CERTIFICATE OF CORRECTION

PATENT NO. : Des. 567,994 S
APPLICATION NO. : 29/262455
DATED : April 29, 2008
INVENTOR(S) : Yu Chung Chan et al.

Page 1 of 7

It is certified that error appears in the above-identified patent and that said Letters Patent is hereby corrected as shown below:

In the Drawings

Title page, illustrative fig. 1 should be deleted and substitute therefore the attached title page consisting of the attached illustrative fig. 1.

The drawing sheets 1-5 consisting of Fig(s) 1-7 should be deleted and substitute therefore the attached drawing sheets 1-5 consisting of Fig(s) 1-7.

Signed and Sealed this

Twenty-sixth Day of January, 2010

David J. Kappos
Director of the United States Patent and Trademark Office
